IDENTIFICATION DEVICE

Veron S. Thomander, Maplewood, N. J., assignor
to Westinghouse Electric Corporation, East
Pittsburgh, Pa., a corporation of Pennsylvania

Application August 15, 1942, Serial No. 454,930

6 Claims. (Cl. 40—20)

This invention relates to identification devices, and it has particular relation to devices for identifying the terminal or binding posts of electrical apparatus.

In the construction of various apparatuses, it is often desirable to employ a number of similar parts for performing different functions. To facilitate selection of the appropriate one of the similar parts, it is customary to provide each of the parts with suitable identification data. In the prior art, such data has been applied by engraving or molding operations.

The application of identification data by engraving or molding operations is unsatisfactory for a number of reasons. Engraving is a tedious and costly process. The application of data by molding increases appreciably the cost of the molds and also increases the number of molds required for applying different identification data to similar parts. In both cases, the application of the identification data to the parts or to the body on which the parts are supported requires the stocking of a separate set of parts or panels for each combination of identification data.

In accordance with the invention, a separate identification element is employed which is secured to a body requiring the identification data. In a preferred embodiment of the invention, the identification element takes the form of an element having a non-circular opening therein proportioned to receive snugly the base portion of an attaching element. The attaching element also has a cap portion which overlies the identification element sufficiently to secure the identification element between the cap portion and the body against which the base portion of the attaching element is placed. Since the identification element may be constructed in an extremely compact design, and since the material for the identification element may be selected to facilitate the application thereto of the identification data by a convenient process, such as printing, the problems of applying the identification data and of stocking the identification elements are materially simplified. The invention may be applied conveniently to the terminal or binding posts of electrical apparatus by providing each terminal post with a head designed to secure the identification element to the electrical apparatus.

It is, therefore, an object of the invention to provide an improved identification assembly for apparatus requiring identification.

It is a further object of the invention to provide an identification element having a non-circular opening therein proportioned to receive

snugly a non-circular portion of an attaching element.

It is a still further object of the invention to provide a terminal post having a head formed with a non-circular periphery designed to receive an identification element having an opening snugly receiving a portion of the head and proportioned to secure the identification element to a body to which the terminal post is secured.

It is another object of the invention to provide an improved method for forming an assembly including a terminal post and an identification element therefor.

Other objects of the invention will be apparent from the following description taken in conjunction with the accompanying drawing in which:

Fig. 1 is a view in top plan with parts broken away of an electrical instrument embodying the invention;

Fig. 2 is a view in side elevation with parts shown in cross-section of a terminal post assembly employed in the instrument of Fig. 1;

Fig. 3 is an exploded view in perspective of a portion of the terminal post assembly shown in Fig. 2; and

Fig. 4 is a view in top plan of an identification element employed in the terminal post assembly of Fig. 2.

Referring to the drawing, Fig. 1 shows an instrument 1 having parts requiring identification data. This instrument may vary appreciably in construction, but for the purpose of discussion it is assumed that the instrument 1 represents an electrical voltmeter having a scale 3, across which a pointer 5 is actuated in accordance with the voltage applied to the instrument. The instrument 1 includes a panel 7 which conveniently may be formed of an insulating material, such as a phenolic resin. This panel supports a number of terminal or binding post assemblies 9 to which conductors L may be connected for the purpose of energizing the voltmeter 1.

In order to identify the terminal posts 9, each terminal post is provided with an identification element 11, 13, 15, 17, 19 or 21. The identification element 11 bears positive and negative polarity markings to indicate that the associated terminal post is always connected to one of the energizing conductors. The remaining identification elements each is marked with a specific voltage to indicate the range of the instrument when energized from the terminal post. For example, when the conductors L energizing the instrument are connected to the terminal posts associated with the identification elements 11 and

21, the application of 150 volts to the instrument produces a full scale deflection of the pointer 5. As a further example, when the conductors L are connected to the terminal posts associated with the identification elements 11 and 17, the application of 90 volts to the instrument produces a full scale deflection of the pointer 5. The construction and operation of a voltmeter similar to that thus far specifically described are well known in the art.

Each of the terminal or binding posts 9 may have a construction similar to that illustrated in Fig. 2. Referring to Fig. 2, it will be observed that the terminal post 9 includes a head 23 which has a screw element 25 connected thereto. The screw element 25 projects through an opening in the panel 7, and is secured thereto by a nut 27 having threaded engagement with the screw element 25. A washer 29 may be placed between the nut 27 and the panel 7. If desired, a lock nut 31 may be employed in conjunction with the nut 27.

The head 23 also carries a screw post 33 which is in threaded engagement with a disc 35. The disc 35 may be attached in any suitable manner to a knob 37 which may be formed of an insulating material, such as a phenolic resin. Although the disc 35 may be cemented to the knob 37, preferably a portion of the disc 35 or a projection thereon is molded in a plastic material, such as a phenolic resin, which is employed for the knob 37. Alternatively, the knob 37 and the disc 35 may be both formed of metal, and may be formed as a unit from a single piece of metal. As illustrated in Fig. 2, the periphery of the knob 37 may be corrugated or knurled to facilitate manual rotation of the knob. As well understood in the art, the disc 35, post 33, head 23, screw element 25, washer 29 and nuts 27 and 31 are formed of an electroconductive material, such as copper or brass. It will be understood that the terminal post 9 is electrically connected to the movement of the instrument 1 or to multipliers or resistors associated therewith. Such a connection is represented by a conductor 39 having a terminal lug 41 clamped between the nut 27 and the washer 29.

Rotation of the knob 37 advances or retracts the disc 35 relative to the head 23 to clamp or release a conductor placed between the disc and the head. To facilitate the location of a conductor therebetween, the head 23 may be provided with a pair of parallel V-shaped grooves 43.

In order to identify the terminal post 9 of Fig. 2, the identification element 21 is secured between the head 23 and the panel 7. The relationship of the identification element 21 to the head 23 is clearly shown in Fig. 3.

Referring to Fig. 3, it will be observed that the head 23 has a non-circular perimeter. Preferably, the head 23 is of polygonal shape, and in the specific embodiment illustrated, the head is of hexagonal shape. The head 23 is divided into a cap portion 23a and a base portion 23b by removing a portion of each corner of the polygonal head 23 to form a seat 45 which conveniently may be of arctate form. By inspection of Fig. 3, it will be observed that the base portion formed by the seats 45 provides a resultant seat having a non-circular perimeter which may be described as a polygonal perimeter having rounded corners.

The identification element 21 has an opening 47 formed therein which is proportioned to receive snugly the base portion 23b of the head 23. By inspection of Figs. 3 and 4, it will be ob-

70 served that the opening 47 is in the form of a polygonal opening, wherein the intersecting planes defining the opening have fillets 49 left in their corners to provide a polygonal opening having rounded corners adapted to receive snugly the base portion 23b of the head.

Because of the non-circular perimeter of the base portion 23b, the identification element 21 cannot rotate with respect to the head 23 when the terminal post is in mounted position on the panel 7. Furthermore, it will be observed that axial movement of the identification element 21 with respect to the terminal post is prevented on one side by the panel 7 and on the opposite side by the corners of the cap portion 23a of the head 23 which overlie the identification element 21.

To prevent rotation of the head 23 with respect to the panel 7, the end of the head 23 which enters the opening 47 may be provided with knurls 51. The knurling may be in any pattern to provide small protuberances capable of penetrating the panel 7 sufficiently to prevent rotation of the head 23 with respect to the panel. In the specific embodiment of Fig. 3, the knurling takes the form of small radial grooves which provide radial edges capable of penetrating the panel 7 for a distance sufficient to prevent rotation of the head. If desired, an annular recess 53 may be provided between the knurling and the screw element 25 to restrict the engagement of the head 23 with the panel 7 to the rim portion of the head.

Since the identification element 21 need not be subjected to excessive stress, any suitable material may be selected therefor. For example, the identification element may be formed from sheet aluminum and the identification data applied thereto may be applied by a printing operation.

Conveniently, the screw element 25, the head 23 and the screw post 33 may be formed from a single piece of polygonal copper or brass stock. Each end of this stock may be turned down and threaded to provide the screw element 25 and the screw post 33. These turning operations may be performed by hand in a suitable lathe or may be 45 performed conveniently in an automatic screw machine. While the stock is in the lathe or screw machine, the corners of the head 23 which are to be positioned adjacent the panel 7 are turned down to provide the arcuate seats 45. It will be observed that a portion only of each corner is turned down to provide a generally polygonal outline for the base portion 23b of the head 23. The slight projections of the untouched portions of the corners of the head 23 project over the seats 45 and are sufficient to retain the identification element 21 in place.

Although the invention has been described with reference to certain specific embodiments thereof, numerous modifications are possible. Therefore, the invention is to be restricted only by the appended claims.

I claim as my invention:

1. In a multipart device, an element having a non-circular opening therein, a head, said head comprising a base portion proportioned to enter and snugly fit said opening, and a cap portion of a size incapable of passing through said opening when said element is in mounted position relative to said head, said base portion being insertable in and removable from said opening in response to movement of said head relative to said element along a line passing through said opening, and means for securing said head to a body to which said element is to be attached with said base portion adjacent the body, said base portion having a

roughened portion projecting through said opening to engage the body and inhibit relative rotation between the body and said head.

2. In an assembly for securing an element in a desired position, an element having a non-circular opening therein, a head, said head comprising a base portion proportioned to enter and snugly fit said opening, and a cap portion of a size incapable of passing through said opening when said head is in mounted position relative to said element, said base portion having sufficient length to pass through said element and present a surface which can be placed in contact with a body to which said element is to be secured without substantially stressing the element, and screw-threaded means cooperating with said head for securing said head to the body to which the element is to be attached with said surface in contact with the body, said element having a surface visible when said element is in secured position on the body.

3. In an identification device, an identification element having a non-circular opening therein, a head, said head comprising a base portion proportioned to enter and snugly fit said opening, and a cap portion of a size incapable of passing through said opening when said identification element is in mounted position relative to said head, said base portion having sufficient length to pass through said identification element and present a surface which can be placed in contact with a body to which said identification element is to be secured without substantially stressing the identification element, and means cooperating with said head for securing said head to a body to which the identification element is to be attached with said surface in contact with the body, said surface being knurled to facilitate a firm engagement of the head with the supporting body, whereby the knurls on said surface prevent movement of said head relative to the supporting body, and the non-circular configuration of said opening prevents rotation of said identification element relative to said head, said identification element having a display surface visible when the identification element is secured to a body.

4. In a multipart device, a polygonal head having sides formed by intersecting planes, portions only of the corners formed by said intersecting planes being removed adjacent one end of said polygonal head to form a base portion having a non-circular perimetric surface of reduced perimetric dimension compared to the remaining polygonal surface of said head, said head being designed to be secured to a body with said base portion contacting the body, and an element having an opening proportioned to re-

ceive snugly said base portion, whereby said element may be secured between said head and a body to which said head is secured, said base portion having a dimension sufficient to project through the opening in said element into contact with the body.

5. In an assembly for securing an element in a desired position, an element having a polygonal opening therein, said opening having surfaces formed by intersecting planes, a portion of the corners formed by the intersecting planes having fillets therein for producing an opening smaller than the full opening defined by said intersecting planes, a head, said head comprising a base portion having a polygonal shape similar to that defined by said intersecting planes and having its corners removed sufficiently to permit said base portion to enter and snugly fit said polygonal opening, and said head comprising a cap portion having a polygonal shape similar to that defined by said intersecting planes and having its corners substantially intact to prevent passage of said cap portion through said polygonal opening, and screw means projecting from said base portion of said head for securing said head and said element to a body, said base portion being proportioned to project through said polygonal opening to contact said body when said head is in attached position on said body, and said element having a display surface visible when said element is secured by said head to a body.

6. In an assembly for securing an element in a desired position, a polygonal head member, a screw element projecting from one end of said polygonal head member, said polygonal head member having portions of the corners formed by the polygonal surfaces thereof removed for a portion only of the length of said head member measured from said one end to provide a non-circular base portion having a perimetric dimension smaller than the perimetric dimension of the remainder of said polygonal head member, and an element having an opening proportioned to receive snugly said base portion, whereby the forcing of said one end adjacent a body by said screw element secures said element against movement relative to said head, said one end being knurled for facilitating the gripping of a body by said one end, said base portion being proportioned to project through said opening into contact with said body when said head is in attached position, and said element having a display surface visible when said first element is secured by said head to a body.

VERNON S. THOMANDER.
